UNITED STATES PATENT OFFICE.

ERNEST WILDHABER, OF BROOKLYN, NEW YORK, ASSIGNOR TO GLEASON WORKS, OF ROCHESTER, NEW YORK, A CORPORATION OF NEW YORK.

METHOD OF AND MACHINE FOR PRODUCING GEARS.

Application filed May 23, 1927, Serial No. 193,611, and in Great Britain and France June 14, 1926.

The present invention relates to gears and particularly to a method and machine for producing longitudinally curved tooth hypoid gears.

5 It has been proposed, heretofore, to produce hypoid gears by cutting the larger member of the pair in a forming or non-generating process and generating the other member in an operation in which the tool 10 and blank are rolled relatively to each other in the manner of a gear meshing with the non-generated member. Gear cutting experience indicates generally, however, that gear pairs produced in a generating or rolling process have a smoother tooth surface 15 finish and will mesh together more quietly than gear pairs where one or both members are non-generated.

The primary object of this invention is to 20 provide a method and apparatus for producing longitudinally curved tooth hypoid gears, of such character that both members of a pair of such gears may be generated.

A further object of this invention is to 25 provide a generating method for gears of the character described, which will be theoretically correct. To this end, gears are generated, according to the present invention, conjugate to basic helicoidal segments, 30 which have the same relation to a system of hypoid gears, as have the rack and crown gear to spur and bevel gears, respectively.

Other objects of the invention will appear hereinafter from the specification and from 35 the recital of the appended claims.

In the drawings:

Figures 1 and 2 are a plan view and a side elevation, respectively, of a pair of gears produced according to this invention;

40 Figures 3 and 4 are a side elevation and plan view, respectively, of a helicoidal segment such as forms the basic member for the generation of gears according to the present invention;

45 Figure 5 is a fragmentary view of a pair of complementary helicoidal segments, such as might be used for the generation of a pair of gears with this invention, in mesh;

50 Figures 6 and 7 are views illustrating diagrammatically in plan and in side elevation, respectively, the pitch surfaces of a pair of gears with angularly disposed non-intersecting axes;

Figures 8 and 9 are a plan view and a

side elevation respectively, illustrating diagrammatically the mesh of a gear constructed according to this invention and a basic helicoidal segment;

55 Figure 10 is a fragmentary sectional view showing the relation between a pair of tools, such as might be employed in producing a pair of gears according to this invention;

60 Figure 11 is a side elevation, partly in section, showing the relation between a pair of grinding wheels such as might be employed in producing a pair of longitudinally curved tooth gears according to one modification of my invention;

65 Figure 12 is a diagrammatic view showing the relation between one of said grinding wheels and the basic helicoidal segment it represents;

70 Figure 13 is a view illustrating diagrammatically a possible modification of my invention; and

75 Figures 14 and 15 are a plan view and side elevation, respectively, showing somewhat diagrammatically one embodiment of a machine for producing gears according to this invention.

80 The present application is a continuation in part of my copending application, Serial No. 38,725, filed June 22, 1925. The present application covers specifically the application of the principles set forth in the prior application mentioned, to the production of longitudinally curved tooth hypoid gears.

85 The purpose of the present invention is to provide a theoretically correct method for generating both members of a pair of longitudinally curved tooth hypoid gears. It is believed that gears produced according to this invention will be quieter in operation and of more satisfactory construction than gears, where one member of the pair is non-generated.

90 One difficulty experienced in the generation of both members of a pair of gears arranged with axes angularly disposed and non-intersecting has been the inability to 100 secure a theoretically correct basic member from which to generate such gears, regardless of their ratio. In bevel gears and spur gears, a pair of gears will mesh correctly together with full line contact when they are 105 capable of meshing with complementary basic members. These basic members are racks for spur gears and crown gears for

bevel gears. The present invention has as its basis the provision of a basic member, comparable to the crown gear in bevel gearing and the rack in spur gearing, from which the tooth structure of gears with non-intersecting axes may be derived and from which the proportions of such gears regardless of ratio may be determined. This basic member is a helicoidal segment and gears are generated according to this invention by rolling the blank and tool relatively to each other as though the blank were meshing with a basic helicoidal segment represented by the tool. The rolling motion will comprise, preferably, a rotary motion of the blank on its axis, a relative movement between the tool and blank about an axis angularly disposed to and offset from the blank axis, and an additional feeding movement between the tool and blank, preferably in the direction of the axis about which the last named movement takes place. The blank may be intermittently or continuously indexed.

The theory upon which the present invention is based will be described more particularly with reference to the accompanying drawings. Figures 1 and 2 show a pair of longitudinally curved tooth hypoid gears 10 and 11, constructed according to one embodiment of this invention. These gears are so arranged relatively to each other that their axes are angularly disposed and non-intersecting. The axis of the gear 10 is indicated at 12 and the axis of the pinion 11 at 13. The relative motion of a pair of gears of this type, as is well known, can be considered, at any instance, as a turning motion about an instantaneous axis 14 and a simultaneous translation along said axis 14. The pitch surfaces 15 and 16 of the gears are hyperboloids of revolution, being produced by movement of the instantaneous axis 14 about the respective axes 12 and 13 of the gears. The pitch surfaces of the gears will contact along the line 14. The teeth 18 of the pinion 11 are preferably disposed outside the pinion pitch surface 16, as with this construction it is possible to increase the size of the pinion over a bevel pinion of a corresponding ratio and so give it increased strength. The teeth 17 of the gear 10 will then lie within the gear pitch surface 15.

Besides the gear 11 there exists an infinite number of other gears which may mesh with the gear 10 in such a way that the line 14 is the instantaneous axis. The pitch hyperboloids of all these gears will contact with the pitch hyperboloid of the gear 10 along the line 14 and at any instant the relative motion of the contacting gears may be considered as a combined sliding and rolling motion about and in the direction of the axis 14. In no case will the ratio of relative sliding and turning be the same for the different gears which may mesh with the gear 10.

The instantaneous relative motion between the gears is, therefore, a helicoidal motion having a different advance or lead for every gear combination of which the gear 10 or gear 11 is a member and which has an instantaneous axis 14. The tooth contact between a third gear and a gear 10 will depend, therefore, not only on the location of the instantaneous axis, but also on the lead or advance per revolution of the instantaneous motion. 75

A consideration of the above facts has resulted in the conclusion that two hypoid gears, such as 10 and 11, will mesh with a third member and will contact with said member along the same lines, if this third member is given not only a rotary motion, but also a translatory motion in the direction of its axis. This third member will have a helicoidal pitch surface which contacts with the pitch surfaces of the gears 10 and 11 along the line 14 and the instantaneous relative motion of this third member with respect to either gear 10 or 11 is identical with the relative motion between these two gears, as will be more fully explained hereafter. Such a third member may be made, hence, the basic member for the production of gears with non-intersecting axes which are theoretically accurate and which mesh with line contact. It follows, therefore, that a hypoid gear may be accurately generated if the blank is given a motion relative to the tool as though it were meshing with a basic helicoidal member represented by the tool. 100

A third member of the considered type is illustrated in Figures 3 and 4. The teeth 24 of this basic helicoidal segment 25 are longitudinally curved and its tooth surfaces 26 have a constant inclination to a plane perpendicular to the axis 27 of the segment. The teeth of this member may be of any suitable curvature. Preferably, however, the tooth surfaces 26 are surfaces of revolution such as might be swept out by a cutting blade 29 moving on the arc of a circle 30. The relations and formulas which determine the shape of the basic member, its lead and its position relative to the blank to be operated upon, and which determine, consequently, the relative positions of tool and blank and their relative motions for generation will now be determined. 110

Referring to Figures 6 and 7, 31 and 32 are the axes of a pair of gears 33 and 34 having hyperboloidal pitch surfaces. These gears contact along the line 35 which is the instantaneous axis. The angles α' and α'' included between the instantaneous axis 35 and the axes 31 and 32 are determined in known manner by the ratio: 120

$$\frac{\sin \alpha'}{\sin \alpha''} = \frac{N'}{N''} \quad (1)$$

where N' and N'' are the tooth numbers of 130

the respective gears. The distances z' and z'' of the respective axes of the two gears from the instantaneous axis 35 are in the relation:

$$5 \quad \frac{z'}{z''} = \frac{\tan a'}{\tan a''} \quad (2)$$

When the axes 31 and 32 are at right angles, $10 \quad a' + a'' = 90^\circ$, and $\sin a'' = \cos a'$ and tangent $a'' = \frac{1}{\tan a'}$.

The above formulas will become:

$$15 \quad \tan a' = \frac{N'}{N''} \quad (1a)$$

and

$$20 \quad \frac{z'}{z''} = \tan^2 a' \quad (2a)$$

In terms of C the distance between the axes of the two gears, which distance is equal to $z' + z''$, formula (2a) becomes:

$$25 \quad z' = C \sin^2 a' \text{ or } z'' = C \cos^2 a'$$

The pitch hyperboloids 33 and 34 which, as stated, may be considered the pitch surfaces of a pair of gears, when rotated about their respective axes 31 and 32, in the inverse ratio of the tooth numbers N' and N'' of the gears, will roll on each other and in addition slide in the direction of their contact line 35. At any instance, the relative motion between the gears is, therefore, a helicoidal motion about the axis 35. The

lead of this motion or advance per revolution can be determined as follows:

$$L = 2\pi z' \tan a'' = 2\pi z'' \tan a' \quad (3)$$

When the axes 31 and 32 are at right angles: 40

$$L = 2\pi \frac{z'}{\tan a'} = 2\pi \frac{z''}{\tan a''} \quad (3a)$$

A helicoidal member 37, shown diagrammatically in Figures 8 and 9, can be constructed so that its pitch surface will contact with the pitch surface 33 of a gear having an axis 31, such as the gear of Figures 6 and 7, along the instantaneous axis 35 and so that at any instant the relative motion between the pitch surface of the helicoidal member 37 and the pitch surface 33 of the gear is identical with the relative motion between the pitch surfaces 33 and 34 of the gears shown in Figures 6 and 7. In other words, the relative motion between the helicoidal member 37 and the gear whose pitch surface is represented at 33 must be, at any instance, a helicoidal motion about the instantaneous axis 35, with a lead as given by formula (3).

The structure and position of the helicoidal member 37 can now be determined. Let L^0 be the lead of the helicoidal member, z^0 the distance of its axis 38 from the instantaneous axis 35, and a^0 the angle between its axis 38 and the instantaneous axis 35, (see Figs. 8 and 9). With the known methods of kinematics, the following formulas can be derived:

$$z^0 = \sin^2 a^0 \left[(z'' - z') + \frac{\tan a'}{\tan a^0} \left(z'' + \frac{z'}{\tan^2 a'} \right) \right] \quad (4)$$

and

$$L^0 = 2\pi \left[\frac{z'}{\tan a'} - \frac{z^0}{\tan a^0} \right] \quad (5)$$

75 z^0 will be negative when the axis 38 of the helicoidal member lies between the instantaneous axis 35 and the axis 31 of the gear 33, as shown in Figure 9, and it will be positive when the axis of the helicoidal member lies further away from the axis of the gear than does the instantaneous axis. Usually the axes of a pair of hypoid gears are disposed at right angles as shown in Figures 1 and 2. Formula (4) under these conditions becomes:

$$85 \quad z^0 = \sin^2 a^0 \left[(z'' - z') + \frac{2z'}{\tan a' \tan a^0} \right], \quad (4a)$$

while formula (5) remains the same. From 90 these formulas it follows that an infinite number of helicoidal members exist which can mesh with a gear of the type referred to and which possess a relative motion of a type identical to that of the gear. Any 95 one of these members may be employed, therefore, as a basic member from which the

gear may be derived. It follows, also, that a gear having a pitch surface 33 capable of meshing with a third member 37, can mesh with a gear having a pitch surface 34 which itself is capable of meshing with a helicoidal member complementary to the member 37. The teeth of the complementary helicoidal segments are naturally curved in opposite hands, and on one segment will lie outside its pitch surface and on the other segment inside its pitch surface.

The relationship between the pair of complementary helicoidal segments, to which the two members of a pair of longitudinally curved tooth hypoid gears may be generated conjugate, is shown diagrammatically in Figure 5. These segments 39 and 40 have longitudinally curved teeth which are of opposite hands. Their teeth interfit one another exactly, the teeth of one member fitting and completely filling the tooth spaces of the other member. The two segments have the same axis 41.

If from the infinite numbers of helicoidal segments which can mesh with the gear of the type referred to, one is chosen whose

axis is at right angles to the instantaneous axis, formulas (4) and (5) become:

$$z^0 = z'' - z' \quad (4^b)$$

and

$$L^0 = 2\pi \frac{z'}{\tan a'} \quad (5^b)$$

The hand or lead of the helicoidal third member, itself, as distinguished from the hand of its teeth depends on the relative position of a pair of gears and may be considered in formula (5) by introducing positive and negative signs. The hand of the helicoidal third member shown in Figures 3 and 4 is right hand. The data with respect to the basic helicoidal segment having been determined, a pair of gears can be readily generated conjugate to each other by cutting one gear by effecting a cutting motion between a tool and a gear blank while simultaneously producing a relative motion between the tool and blank as though the blank were meshing with the basic helicoidal segment represented by the tool, and by generating the other gear in a similar manner conjugate to a helicoidal segment complementary to the segment to which the first gear was generated conjugate.

Gears pairs produced according to this invention will be proportioned preferably according to the principles disclosed in my prior Patent No. 1,622,555, issued March 29, 1927.

Gears may be cut with this invention with a reciprocating tool which is moved in a curved path or with a continuously rotating tool, as a face mill. The required cutting motion will be imparted to the tool and simultaneously a relative movement will be produced between the tool and blank as though the blank were meshing with the basic segment represented by the tool. This relative movement preferably will consist of a rotation of the blank on its axis, of a relative movement between the tool and blank about the axis of the helicoidal segment, which axis will be angularly disposed to and offset from the axis of the blank and of a relative feed movement between the tool and blank in the direction of the axis of the helicoidal segment. The tool may be positioned with reference to the blank according to the general principles employed in cutting spiral (longitudinally curved tooth) bevel gears, and gears of any desired spiral angle may be cut. One gear of a pair will be generated conjugate to one helicoidal segment and the other member of the pair will be generated conjugate to a helicoidal segment complementary to the first. The cutting edges of the tools may be straight or curved.

In Figure 10, I have shown a pair of rotary annular face mills 55 and 56 such as might be employed for producing gears with this invention conjugate to complementary

basic helicoidal segments. One tool 56 is a male tool representing a tooth surface or tooth surfaces of one segment. The other tool 55 is a female tool interfitting exactly with the male tool and representing a tooth surface or tooth surfaces of a segment complementary to the segment whose tooth surfaces are swept out by the tool 56. The axes of the two tools are at 57 and 58, respectively. The line 59 indicates the pitch surfaces of the complementary segments whose axes coincide and are indicated at 60.

The tools 55 and 56 are provided with straight profiles, representing the straight profiled tooth surfaces of complementary basic segments. In Figure 11 a pair of grinding wheels 61 and 62 are shown having grinding surfaces 63 and 64 and 65 and 66, respectively, which are portions of spherical surfaces, representing portions of the side tooth surfaces of basic helicoidal segments whose tooth surfaces are portions of spherical surfaces of revolution.

Figure 12 shows the relation between one of these tools 62 and the basic helicoidal segment 68 which the tool represents. Adjacent tooth sides of the basic helicoidal segment 68 are parts of convex and concave spherical surfaces, respectively, which may have equal sphere radii 69 and 70. Adjacent tooth surfaces have centers 71, 72, 73, 74, 75 and 76, etc. located in two helices 78 and 79. The centers of the convex surfaces of the segment 68, represented by the grinding wheel 62, are located on the helix 78, while those of the concave surfaces are located on the helix 79. The two adjacent spherical sides of a tooth of the basic segment may be represented by the wheel 62 when the axis 80 of the wheel 62 is so inclined as to pass through the centers 74 and 75 of the tooth sides. In a similar manner, the two adjacent spherical tooth sides of the complementary basic segment may be represented by the grinding wheel 61 when its axis 81 is so inclined as to pass through the centers 75 and 76 of adjacent tooth sides of the complementary segment. By positioning the tools in the manner described, a pair of male tools may be employed to produce conjugate gears, and with such tools it is possible to produce teeth of tapering depth.

In certain cases, for the sake, especially, of structural advantages obtainable in machines employed for practising this invention, a slight departure from theoretical requirements is possible. So, a pair of basic helicoidal segments may be employed in generating a pair of gears according to this invention which are not exactly complementary, as the segments 83 and 84 shown in Figure 13 and which may be represented by the face mills 85 and 86. These segments have teeth arranged on helicoidal surfaces

87 and 88. The departure from strict theory in the case illustrated is analogous to structural departures often made in bevel gear cutting machines, where the machines are so 6 constructed that the generating motion imparted between the tool and blank is strictly not a relative motion as though the blank were meshing with a true crown gear, but a relative motion in which the tool represents 10 a basic gear having a plane top surface and a conical pitch surface.

One form of machine for practising this invention is shown in Figures 14 and 15. In the embodiment illustrated, a rotary angular face mill 90 is employed. This tool 15 may be so constructed that in any one operation it finish cuts one tooth side of the blank only or may be provided with cutting edges adapted to simultaneously finish cut 20 adjacent tooth sides of a blank. The cutting edges of the tool represent tooth surfaces of the basic helicoidal segment to which the gear to be cut is to be generated conjugate. The tool 90 is journaled in an upright 91 25 and is adjustable thereon and with reference to the cradle 92 in such manner as to permit of it being positioned in proper cutting engagement with the blank, indicated at B.

The cradle or carrier 92 upon which the 30 tool is supported is mounted for rotation or oscillation in the frame 93. The axis of the cradle represents the axis of the basic helicoidal segment. The blank is secured to a spindle 94 which is journaled in a slide 95 35 which can be adjusted vertically on an upright 96 which in turn may be angularly adjusted in any suitable manner upon the table or slide 97. The angular adjustment of the upright 96 permits of bringing the blank 40 into the proper tangential plane for cutting, while the vertical adjustment of the slide 95 permits of offsetting the axis of the blank any desired distance from the axis of the cradle, whereby to position the blank axis 45 in the required relation to the axis of the helicoidal segment.

The slide 97 is provided with guide rails 98 which move in guide ways formed in the base 99 secured to or integral with the frame 50 93. The movement of the slide or carrier 97 is in a direction parallel to the axis of the cradle 92.

During generation, the tool is rotated on its axis in engagement with the blank, the blank spindle rotates on its axis, the cradle 55 92 rotates on its axis and simultaneously a feed movement is imparted to the slide 97 toward or away from the cradle, depending on the direction of rotation of the blank and cradle. The rotation of the blank, the rotation of the cradle and the feed of the slide 97 60 are all timed together so that the relative movement of tool and blank corresponds to that of a gear meshing with a basic helicoidal segment represented by the tool. Gearing

for imparting to the various parts their required motion is indicated rather diagrammatically in Figures 18 and 19. So the cutter is shown as continuously rotated from the motor 100 through the gears 101 and 102. 70 The cradle 92 has a worm wheel segment 104 secured to it and is driven by the worm 105 which meshes with this segment. The worm is mounted upon a shaft 106 which is driven through the bevel gears 107, the shaft 108, 75 and the bevel gears 109 from the main drive shaft 110, which is driven by the motor 111 through the bevel gears 112. The shaft 110 carries midway its length a bevel gear 113 which meshes with a bevel gear 114 on a vertical shaft 115. The vertical shaft 115 carries at its upper end a spur gear 116 forming one of a set of change gears which transmit the rotation of the shaft 115 to the worm shaft 117 carrying a worm 118 which meshes 80 with a worm wheel 119 secured to the blank spindle 94. At its outer end the shaft 110 carries a spur gear 120 forming one of a set of change gears which transmits the rotation of the shaft 110 to a feed screw 121 which is 85 mounted in the base 99 and which threads into a nut 122 secured to the slide 97.

In operation the tool rotates in engagement with the blank, while the blank rotates on its axis and while the cradle slowly 95 moves about its axis and the blank slide 97 is given a movement in a direction parallel to the cradle axis. The last three motions are in timed relation and generate the tooth profiles. When the cradle has been so turned 100 that a tooth profile or adjacent tooth profiles are completely generated, the tool and blank will be withdrawn relatively to each other and the blank indexed. The blank will then be returned into engagement with the tool 105 and the cycle will commence anew with the generating operation proceeding upon a new tooth face or tooth faces of the blank. For the sake of clearness, the mechanism for effecting the relative withdrawal and return 110 for indexing and the mechanism for effecting the indexing itself have been omitted. Any usual or suitable mechanism for these purposes may be employed, however, as will be readily understood. It will be understood, 115 also, that instead of intermittently indexing the blank, the blank may be continuously indexed, as in a hobbing operation and the tool, then, will be a hobbing tool, either of the face mill or worm type.

Instead of a continuously rotating tool, it is obvious that a reciprocating tool may be employed instead, the tool being reciprocated in a curved path across the face of the blank. In any case, however, the points of the cutting edges of the tool will move along lines lying in parallel planes, that is, the cutting edges will move along a line of constant curvature, representing a tooth side of the basic helicoidal segment. 125 130

While I have illustrated one embodiment of a machine for practicing this invention, it will be understood that various other types of machines may be employed, also. In general, the methods employed for the cutting of bevel gears may be applied to the cutting of the hypoid gears described, when so modified as to allow for the helicoidal nature of the basic segments.

10 While I have described my invention particularly with reference to hypoid gears having tapered bodies it is obvious, also, that the invention relates to other forms of gears with non-intersecting axes, as worm gears.

15 Gears which are derived from a basic element whose tooth surfaces are surfaces of revolution can readily be ground and the term "cutting" as employed in the specification and claims is intended to include the 20 production of gears by a grinding operation also.

In general, it may be said that while I have illustrated and described certain preferred embodiments of my invention, it will 25 be understood that the invention is capable of further modification within its limits and the scope of the appended claims and that this application is intended to cover any 30 variations, uses, or adaptations of my invention, following, in general, the principles of the invention and including such departures from the present disclosure as come 35 within known or customary practice in the gear art and as may be applied to the essential features hereinbefore set forth, and as fall within the limits of the appended claims.

Having thus described my invention, what I claim is:

1. The method of producing a gear which 40 consists in cutting its side tooth surfaces by moving a tool in a curved path across the face of a gear blank while simultaneously producing an additional relative movement between the tool and blank corresponding to that of a gear meshing with a helicoidal segment.

2. The method of producing a gear which 45 consists in cutting its side tooth surfaces by moving a tool in a circular arcuate path across the face of a gear blank while simultaneously producing an additional relative movement between the tool and blank corresponding to that of a gear meshing with a helicoidal segment.

3. The method of producing a gear which 50 consists in cutting its side tooth surfaces by rotating an annular face mill in engagement with a gear blank while simultaneously producing an additional relative movement between the tool and blank corresponding to that of a gear meshing with a helicoidal segment.

4. The method of producing a gear which 55 consists in moving a tool in a curved path 60 across the face of a gear blank so that points

of its cutting edge move along lines lying in parallel planes, while simultaneously producing an additional relative movement between the tool and blank corresponding to that of a gear meshing with a helicoidal segment. .

5. The method of producing a gear which 65 consists in cutting its side tooth surfaces by moving a tool in a curved path across the face of a gear blank while rotating the 70 blank on its axis and simultaneously producing an additional relative movement between the tool and blank about an axis angularly disposed to and offset from the blank axis and simultaneously and in timed 75 relation to the two last named movements imparting a feed movement between the tool and blank in the direction of the last named axis.

6. The method of producing a gear which 80 consists in cutting its side tooth surfaces by moving a tool in a curved path across the face of a gear blank while rotating the blank on its axis and simultaneously producing a relative movement between the tool 85 and blank about an axis offset from the blank axis and simultaneously and in timed 90 relation to the two last named movements imparting a relative feed movement between the tool and blank at an angle to the blank 95 axis.

7. The method of producing a gear which 100 consists in cutting its side tooth surfaces by moving a tool in a circular arcuate path across the face of a gear blank, while rotating the blank on its axis, simultaneously producing an additional relative movement between the tool and blank about an axis angularly disposed to and offset from the blank axis and simultaneously and in timed 105 relation to the two last named movements imparting a feed movement between the tool and blank in the direction of the last named axis.

8. The method of producing a gear which 110 consists in cutting its side tooth surfaces by rotating an annular face mill in engagement with a gear blank, while rotating the blank on its axis, simultaneously producing an additional relative movement between the tool and blank about an axis angularly disposed to and offset from the blank axis and simultaneously and in timed 115 relation to the two last named movements imparting a feed movement between the tool and blank in the direction of the last named axis.

9. The method of producing a gear which 120 consists in cutting its side tooth surfaces by moving a tool in a curved path across the face of a gear blank so that points of its cutting edge move along lines lying in parallel planes, while rotating the blank on its axis, simultaneously producing an additional relative movement between the tool and blank about an axis angularly disposed 125

to and offset from the blank axis and simultaneously and in timed relation to the two last named movements imparting a feed movement between the tool and blank in the direction of the last named axis.

10. The method of producing a pair of gears which are adapted to mesh with axes non-intersecting and non-parallel, which consists in generating the side tooth surfaces of one member of the pair conjugate to a basic helicoidal segment having longitudinally curved teeth and generating the side tooth surfaces of the other member of the pair conjugate to a basic helicoidal segment complementary to the first segment.

11. The method of producing a pair of gears which are adapted to mesh with axes non-intersecting and non-parallel, which consists in generating the side tooth surfaces of one member of the pair conjugate to a basic helicoidal segment provided with teeth whose sides are surfaces of revolution, and in generating the side tooth surfaces of the other member of the pair conjugate to a basic helicoidal segment complementary to the first segment.

12. The method of producing a pair of gears which are adapted to mesh with axes non-intersecting and non-parallel, which consists in generating the side tooth surfaces of one member of the pair conjugate to a basic helicoidal segment having longitudinally curved teeth whose side tooth surfaces are of constant profile and such as might be generated by a line, the points of which move in parallel planes, and in generating the side tooth surfaces of the other member of the pair conjugate to a basic helicoidal segment complementary to the first segment.

13. In a machine for producing gears, a blank support, a tool, means for adjusting the tool and blank support into cutting engagement, means for moving the tool in a curved path across the face of the blank and means for simultaneously imparting an additional relative movement between the tool and blank corresponding to that of a gear meshing with a helicoidal segment.

14. In a machine for producing gears, a blank support, a tool, means for adjusting the tool and blank supports into cutting engagement, means for moving the tool in a circular arcuate path across the face of a gear blank, and means for simultaneously imparting an additional relative movement between the tool and blank corresponding to that of a gear meshing with a basic helicoidal segment.

15. In a machine for producing gears, a blank support, a tool, means for adjusting the tool and blank support into cutting relation means for moving the tool in a curved path across the face of a gear blank so that points in its cutting edge move along lines lying in parallel planes, and means for si-

multaneously imparting an additional relative movement between the tool and blank corresponding to that of a gear meshing with a helicoidal segment.

16. In a machine for producing gears, a blank support, a tool support, a rotary annular face mill journaled in said tool support, means for adjusting the tool and blank supports into cutting relation, means for rotating the face mill on its axis in engagement with the blank, and means for simultaneously imparting an additional relative movement between the tool and blank corresponding to that of a gear meshing with a basic helicoidal segment.

17. In a machine for producing gears, a blank support, a tool, means for adjusting the tool and blank support into cutting relation, means for moving the tool in a curved path across the face of a gear blank, means for rotating the blank on its axis while in engagement with the tool, means for simultaneously imparting an additional relative movement between the tool and blank about an axis angularly disposed to and offset from the blank axis, and means for simultaneously and in timed relation to the two last named movements producing a relative feed movement between the tool and blank in the direction of the last named axis.

18. In a machine for producing gears, a blank support, a tool, means for adjusting the blank support and tool into cutting relation, means for moving the tool in a circular arcuate path across the face of a gear blank, means for rotating the blank on its axis while in engagement with the tool, means for simultaneously imparting an additional relative movement between the tool and blank about an axis angularly disposed to and offset from the blank axis, and means for simultaneously and in timed relation to the two last named movements producing a relative feed movement between the tool and blank in the direction of the last named axis.

19. In a machine for producing gears, a blank support, a tool support, a rotary annular face mill journaled in said tool support, means for adjusting the tool and blank supports into cutting relation, means for rotating the tool in engagement with the blank, means for rotating the blank on its axis while in engagement with the tool, means for simultaneously imparting an additional relative movement between the tool and blank about an axis angularly disposed to and offset from the blank axis and means for simultaneously and in timed relation to the two last named movements producing a relative feed movement between the tool and blank in the direction of the last named axis.

20. In a machine for producing gears, a tool support, a tool movably mounted there-

- on, a blank support, a rotatable blank spindle journaled therein, a frame, a carrier, upon which one of said supports is mounted, journaled in said frame, means for positioning the blank support with its axis offset from the axis of said carrier, means for adjusting the tool and blank into cutting relation, means for moving the tool in a curved path across the face of the blank, means for simultaneously rotating the blank spindle on its axis, means for simultaneously moving the carrier about its axis and means for simultaneously and in timed relation to the two last named movements imparting a feed movement between the tool and blank in the direction of the last named axis.
21. In a machine for producing gears, a tool support, a tool movably mounted thereon, a blank support, a rotatable blank spindle journaled therein, a frame, a carrier, upon which one of said supports is mounted, journaled in said frame, means for positioning the blank spindle with its axis offset from the axis of said carrier, means for adjusting the tool and blank into cutting relation, means for moving the tool in a circular arcuate path across the face of a gear blank, means for simultaneously rotating the blank spindle on its axis, means for simultaneously moving the carrier about its axis, and means for simultaneously and in timed relation to the two last named movements imparting a feed movement between the tool and blank in the direction of the last named axis.
22. In a machine for producing gears, a tool support, a rotary annular face mill journaled therein, a blank support, a rotatable blank spindle journaled therein, a frame, a carrier, upon which one of said supports is mounted, journaled in said frame, means for positioning the blank spindle with its axis offset from the axis of said carrier, means for adjusting the tool and blank into cutting relation, means for rotating the tool in engagement with the blank, means for simultaneously rotating the blank spindle on its axis, means for simultaneously moving the carrier about its axis, and means for simultaneously and in timed relation to the two last named movements imparting a feed movement between the tool and blank in the direction of the last named axis.
23. In a machine for producing gears, a tool support, a tool movably mounted thereon, a blank support, a rotatable blank spindle journaled therein, a frame, a carrier, upon which one of said supports is mounted, journaled in said frame, means for positioning the blank spindle with its axis offset from the axis of said carrier, means for adjusting the tool and blank into cutting relation, means for moving the tool in a curved path across the face of the blank, and means for simultaneously rotating the blank on its axis, the carrier on its axis, and moving said slide on the frame to generate the tooth profiles.
24. In a machine for producing gears, a tool support, a tool movably mounted thereon, a blank support, a blank spindle journaled therein, a frame, a carrier, upon which one of said supports is mounted, journaled in said frame, a slide, upon which the other of said supports is mounted, slidable on said frame in a direction parallel to the axis of said carrier, means for positioning the blank spindle with its axis offset from the axis of said carrier, means for adjusting the tool and blank into cutting position, means for moving the tool in a circular arcuate path across the face of the blank, means for simultaneously rotating the blank spindle on its axis, means for simultaneously moving the carrier about its axis, and means for simultaneously and in timed relation to the two last named movements imparting movement to said slide.
25. In a machine for producing gears, a tool support, a rotary annular face mill journaled therein, a blank support, a blank spindle journaled therein, a frame, a carrier, upon which one of said supports is mounted, journaled in said frame, a slide, upon which the other of said supports is mounted, slidable on said frame in a direction parallel to the axis of said carrier, means for positioning the blank spindle with its axis offset from the axis of said carrier, means for adjusting the tool and blank into cutting relation, means for rotating the tool in engagement with the blank, means for simultaneously rotating the blank spindle on its axis, means for simultaneously moving the carrier on its axis, and means for simultaneously and in timed relation to the two last named movements imparting movement to said slide.

ERNEST WILDHABER.
